BASCOM Q. AUSTIN, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed October 11, 1919. Serial No. 330,121.

My invention relates to control apparatus and to systems of control for dynamo-electric machines, and it has special relation to the combined automatic and manual control of electric railway motors and the like.

In the operation of railway vehicles by means of automatic control systems, such up-grades may be encountered that an accelerating current of sufficient proportions may be drawn to cause the current relay or limit switch to stick in its upper or open-circuit position, whereby further control operation, which is dependent upon the dropping of the current relay to its lower or circuit-closing position, is prevented. Various schemes have been proposed in the prior art for allowing the motorman, under the abnormal conditions mentioned, to manually effect control of the motors, but, in practically all such cases, it was almost impossible to prevent the controller from taking more than one operating step, thereby producing too rapid an acceleration, accompanied by a relatively high current, unless the motorman exercised very great skill, including, in many instances, a precisely-timed duration of pressure upon a push button, or the like.

One object of my present invention, therefore, is to provide control apparatus, in a system of the above-indicated character, whereby manual control of the railway vehicle may be effected whenever the limit switch sticks in its upper position and, at the same time, the main controller will be positively prevented from taking more than one notch unless the motorman voluntarily follows a certain cycle of control manipulation.

More specifically stated, it is the object of my invention to provide a double-coil notching relay which is so associated with the main controller and an auxiliary switch that the desired functions are automatically performed in such manner that, normally, the customary acceleration under the control of the current relay is effected step-by-step, whereas manual control, producing movement of only one step at a time, may be effected by the motorman by repeated manipulation of the additional switch mentioned.

Other minor objects of my invention will become evident from the following detailed

description taken in conjunction with the accompanying drawings, wherein—

The single figure is a view, in elevation, of the preferred form of my notching relay.

Referring to the drawing, the preferred structure of my notching relay comprises a suitable base-plate or panel 125 to which are secured a plurality of supporting brackets or standards 126 and 127 for the respective magnet coils 26 and 27, which are transversely related for the purpose of permitting ready interconnection of the several contact members and a minimum number thereof. The magnet coil 26 is provided with a suitable central core 128 for coacting with the magnetizable armature 28, one end of which is pivotally secured to a bent arm or strip 129 which is rigidly attached to the core 128 and the supporting bracket 126. A coil spring 130 serves to bias the armature 28 to the illustrated lower or de-energized position, the spring acting between a small bracket 131 secured to the supporting bracket 126 and one end of a lever 132, the opposite end of which is rigidly fastened to the armature 28. For the purpose of adjusting the tension of the spring 130 to the desired degree, a small bolt 133, which fulcrums against the arm 129, serves to vary the position of the lever 132 and, furthermore, the spring 130 has a screw-threaded connection with the small bracket 131.

The free end of the armature 28 is provided with an extension member 134 of insulating material, the contact clip 31 being electrically secured to the armature 28, while the contact clip 30 is fastened to the insulating member 134 and has no electrical connection with the armature 28.

The other magnet coil 27 is provided with similar accessories including a central core 136, a bent supporting arm 137 for the armature 29, a biasing spring 138 and an adjustable lever arm 139. In addition, a channel-shaped insulating member 33 is secured to the free end of the armature 29 and carries the contact plates 34 and 35 on the opposite inner surfaces of the channel arms. The contact member 32 constitutes a tip on the free end of the armature 29.

The mechanical operation of the apparatus illustrated in the figure need be only briefly described. In the normal illustrated position, a circuit is established from con-

ductor 82 to supporting arm 129, armature 28, contact clip 31, contact plate 32, armature 29, supporting arm 137 and conductor 83. Such circuit is interrupted by the energization of the actuating coil 26 and the consequent upward movement of the armature 28.

When the other magnet coil 27 is energized, the armature 29 moves toward the right to effect engagement between the contact clip 31 and the contact plate 34. If, under such conditions, the other magnet coil 26 is energized, the armature 28 is lifted into a position to effect engagement between the contact clip 30 and the contact plate 35.

I do not wish to be restricted to the specific structural details or arrangement of parts herein set forth, as various modifications thereof may be made without departing from the spirit and scope of my invention. I desire, therefore, that only such limitations shall be imposed as are indicated in the appended claims.

I claim as my invention:

1. Control apparatus comprising a plurality of transversely-related magnet coils having armatures biased to their open positions,

an insulating extension on one of said armatures, a plurality of contact members on opposite sides of said extension, a channel-shaped insulating member secured to another armature, and three independent contact members for co-operating with the first-named contact members and located two on one side and one on the opposite side of the channel-shaped member.

2. Control apparatus comprising a plurality of magnet coils, a plurality of armatures therefor extending at right angles and adapted, when de-energized, to fall to their open positions, a plurality of insulated contact members controlled by, and extending substantially parallel to, one of said armatures, a substantially U-shaped insulating member secured to another armature, and three contact members secured two on one side and one on the opposite side of said insulating member for co-operating with the first-named contact members.

In testimony whereof, I have hereunto subscribed my name this 2nd day of Oct. 1919.

BASCUM O. AUSTIN.
